UNITED STATES PATENT OFFICE.

LESTER J. CRAWFORD, OF ELECTRA, TEXAS.

ENGINE CONTROL.

1,169,620.

Specification of Letters Patent. Patented Jan. 25, 1916.

Application filed May 29, 1915. Serial No. 31,236.

To all whom it may concern:

Be it known that I, LESTER J. CRAWFORD, a citizen of the United States, and a resident of Electra, in the county of Wichita and State of Texas, have invented a new and Improved Engine Control, of which the following is a full, clear, and exact description.

My invention relates to engine controls, and has reference more particularly to means for controlling an internal combustion engine and which is adapted to prevent fuel combustion when the power-transmitting element, for any reason, has interrupted the transmission of energy.

An object of the invention is to provide a simple, inexpensive and efficient means for controlling an internal combustion engine from the driving element.

20 A further object of the invention is to provide a control for the air supply of the carburetor or mixing chamber which is operable from the power transmission means of an internal combustion engine.

25 A still further object of the invention is to provide an engine control whereby internal combustion engines left to run unattended will not run away when their power transmitting element has ruptured, and 30 which will prevent the burning of the engine clutches and belt if the driving element slips.

With the above and other objects in view, the nature of which will more fully appear 35 as the description proceeds, the invention consists in the novel construction, combination and arrangement of parts as herein fully described, illustrated and claimed.

In the accompanying drawings, forming 40 part of the application, similar characters of reference indicate corresponding parts in all the views.

Figure 1 is an end elevation of a gas engine provided with my governing means; 45 Fig. 2 is a side elevation of Fig. 1; Fig. 3 is an enlarged view of the governing means; Fig. 4 is a similar view showing the reverse operation of the governor to what is shown in Fig. 3; Fig. 5 is a modified structure of 50 the governing means; and Fig. 6 is a further modification thereof.

Referring to the drawings, 7 represents an engine the carburetor or mixing chamber 8 of which has a butterfly valve for controlling the fuel mixture leading to the engine and controlling from a fly-wheel gov-

ernor 9, or any other governor driven from the main shaft of the engine. The engine is also provided with a pulley 10 which carries a belt 11 constituting the power-transmitting element of the motor or engine.

Engaging the under side of the belt 11 is a pulley 12 which drives a ball governor 13 mounted on an extension of the engine frame. The ball governor 13 carries a collar 14 which is adapted to participate in the axial movement thereof but which does not rotate with the governor. An arm 15 extends from said collar. A rod 16 passes through the arm 15 and constitutes a guide therefor when said arm moves with the collar 14. The said rod also resists the tendency of the collar 14 to rotate with the governor. The arm 15 carries an extension 17. This extension normally engages a damper or valve 18 of an air passage 19 of the carburetor 8. As shown in Fig. 3, the damper 18 is open when the movement of the governor is arrested or the speed thereof greatly reduced, consequently admitting air to the carburetor and greatly diluting the fuel mixture, rendering the combustion ineffective and thus stopping the engine. The speed of the governor 13 will be greatly reduced if the belt 11 slips on the pulley 10 or, if the belt 11 slips off the pulley the governor 13 will stop and, consequently, the damper 18 will be opened and the engine will stop. A rupture of the belt will produce the same result.

When, in lieu of diluting the mixture, it is desired to choke the engine by enriching the mixture, the extension 17 of the arm 15 is swung to the position indicated in Fig. 4. In this case, the damper 18 carries a weight 20 which normally tends to keep the damper open. When the belt slips or breaks, the governor will close the damper and, therefore, enrich the mixture, which will choke the engine.

In Fig. 5 the damper 18 with the weight 20 is connected to the arm 15 by a chain 21 which is in alinement with the weight. A reduction in the speed of the governor or the stopping of the same will open the damper. That is, the action shown in Fig. 5 is similar to the action shown in Fig. 3. In Fig. 6 the modification shown operates similarly to that shown in Fig. 4. In this case the damper 18 is not provided with a counterweight, as gravity tends to close the damper the same as in Fig. 3. The chain 21

connecting the arm to the damper raises the same against gravity.

From the above description it will be noted that the auxiliary governing device, which is operable from the power transmitting element, will interfere with the internal combustion of the gases within the engine if the power-transmitting element does not travel at the proper velocity or its travel is interrupted altogether, as may be possible in the case of a rupture. The provision of such governing means will prevent the burning of the engine clutches and belt due to the slipping of the belt on the driving pulley, and it will also dispense with the special attendance necessary for that purpose.

While I have described the principle of operation, together with the device which I now consider to be the best embodiment thereof, I desire to have it understood that the device shown is merely illustrative and that such changes may be made as are within the scope of the appended claims.

I claim:

1. In combination, an internal combustion engine including a carbureter or mixing chamber, a governor, means for transmitting power from the engine adapted to drive the governor, an arm adapted to participate in the movement of the governor, said carbureter or mixing chamber having an air damper, and an operative extension from the arm to the damper.
2. In combination, an internal combustion engine having a carbureter, a belt for transmitting power from the engine, a governor, a pulley for driving the governor en-

gaging the belt, an arm adapted to participate in the movement of the governor, said carbureter or mixing chamber having an air damper, and an extension carried by the arm and operatively engaging said air damper.

3. An internal combustion engine control comprising a governor, a pulley for driving the same adapted to be operated by the means for transmitting the power from the engine, an arm associated with the governor and adapted to participate in the movements thereof, and an extension from said arm adapted to operatively engage the fuel mixture supplying means of the engine.

4. In combination, an internal combustion engine having a carbureter or mixing chamber, a belt for transmitting power from the engine, a governor, a pulley for driving said governor engaging the under side of the belt, an arm extending laterally from said governor and adapted to participate in the movements thereof, means for guiding said arm, said carbureter or mixing chamber having an air damper, and an extension pivotally mounted on said arm and adapted to engage said damper, whereby said damper can be optionally maintained either closed or open in the inoperative position of the governor.

In testimony whereof I have signed my name to this specification in the presence of two subscribing witnesses.

LESTER J. CRAWFORD.
